SELF-PROPELLED MACHINE FOR HANDLING
FORGINGSHerbert Dienenthal and Theo Zimmermann,
Siegen, Westphalia, GermanyApplication November 16, 1938, Serial No. 240,764
In Germany November 18, 1937

6 Claims. (Cl. 78—96)

Self-propelling machines for holding and turning heavy work to be forged are known in which a device which carries the tongs for holding the work comprises a number of parts which are able to make angular movements relatively one to another, and pressure or tension springs, which are fitted between these parts take up the additional load which occurs during forging. However, when a machine of this kind is actually used, it has been found that the device which carries the tongs behaves as if it were almost entirely rigid since the springs are too short to act as effective buffers. A further disadvantage is that in the known machine the carrier for the tongs is supported by two lifting cylinders which act independently. It is then impossible to prevent the movements of the lifting cylinders differing somewhat from one another, the result of which is that the carrier does not maintain a horizontal position as is desired when forging.

Now the object of the present invention is to provide an apparatus of the kind described in which the aforesaid disadvantages are obviated. According to the invention the carrier for the tongs is resiliently suspended from four points on a linkage which is actuated by a single lifting cylinder. In one preferred form of construction a pair of bell-crank levers is pivoted at each side to the frame of the machine, and the levers of each pair are linked together by a bar connected to the end of one arm of each of the levers while to the ends of the other arms of the four levers are pivoted four upright rods which carry long helical springs on which the carrier for the tongs is supported. These springs take up the weight of the carrier which is distributed uniformly over the four points of suspension and they are able to support and hold the carrier securely in the horizontal position in which it is always set by means of the lifting cylinder which acts on the linkage. Under the additional load which occurs during forging the springs yield uniformly as a whole in a vertical direction, that is to say in the direction in which the additional load acts.

Further, in accordance also with the invention, the linkage may be provided on both sides of the carrier with a buffer frame which is also connected to the aforesaid bell-crank levers and forms with them and the aforesaid bar a parallelogram linkage. The buffer frames are held in a central position by long helical springs which lie in the direction of the axis of the carrier, and tend to hold the carrier resiliently in

this position. The carrier is therefore able to make longitudinal movements and can yield under the load which occurs owing to extension during forging while the vertical supporting springs can swing about the pivots on which the rods which support them are mounted. The carrier therefore always maintains its horizontal position.

A constructional embodiment of a machine in accordance with the invention is illustrated by way of example in the accompanying drawings, in which

Figure 1 is a side elevation of the machine.

Figure 2 shows the central portion of the machine with the carrier for the tongs displaced.

Figure 3 shows three sections on the lines A—B and C—D of Figure 2 respectively.

Figure 4 is a broken-off vertical section on the line A—A of Figure 5, and

Figure 5 is a broken-off horizontal section on line B—B of Figure 4.

Referring to the drawings, the frame 1 of the self-propelled machine is supported on wheels 2, 3, of which the steering wheel 2 is driven by a motor 4. The driving gear of the vehicle has two separate controls. For fast running for carrying and conveying the billets to be forged, the motor is controlled by means of a controlling drum. When forging, on the other hand, the machine can be intermittently moved forwards or backwards by foot-actuated pedals in accordance with the feed necessary during forging.

On pivots 5 and 6 at each longitudinal side of the frame 1 are pivotally mounted bell-crank levers 7, 8 which are connected transversely in pairs by pivot bars 9, 10 respectively, and longitudinally in pairs by rods 11. A lifting cylinder 12 in the centre of the machine acts on the pivot bar 10. The lifting cylinder (Figures 4 and 5) is supported through trunnion pins c by brackets d carried by a transverse plate e which is secured at each end to frame 1. Piston f carries piston rod a which is secured to pivot bar 10. On each side of the piston the cylinder is in communication through pipes g, h and suitable valves with a source of fluid under pressure, whereby the piston may be reciprocated to rock bell-crank levers 8 and, through rods 11, levers 7. The cylinder rocks in response to changes in elevation of bar 10. The other ends of the levers carry, on pivots 13, 14, long vertical bolts 15 and 16 around which are disposed helical springs 17 and 18 on which supporting arms 19, 20 for the member 21 which

carries the tongs 33 are mounted by means of separate sliding members having lateral pivots 22, 23 which can turn in the supporting arms 19, 20. There are also linked to the pivots 13 and 14 on each longitudinal side of the machine buffer frames 24 having eyes 25 and 26 by means of which a rod 29 which is fixed to eyes 27, 28 of the carrier 21 is guided. Around the rod are fitted bushes 30 and 31 having flanged ends against which a long helical spring 32 bears at each side of the machine. The helical springs act, through the agency of the bushes 30, 31, uniformly on both sides of the machine against the eyes 27 and 28 of the carrier and therefore tend to hold the carrier in the central position. The actual tongs 33 for holding the work to be forged are revolvably mounted in the carrier 21 on a rigid holder 35. It may be opened in known manner from the driver's seat 36 and can be closed and also rotated. During forging the springs 17 housed in frames 37, which are guided on the rods 15, are stressed. The springs are pretensioned to such an extent that they support the carrier 21 together with the tongs and the work to be forged in a horizontal position on the four points of suspension. These parts can be raised and lowered by means of the lifting cylinder 12, the horizontal position being maintained. When an additional load occurs, for example owing to a hammer blow when forging, the springs 17 and 18 yield in the vertical direction, that is to say in the direction in which the additional load is exerted. Horizontal displacements are taken up by the springs 32, one or other of the sleeves 30 and 31 being shifted on the bolt 29, as shown in Figure 2. The rods 15 and 16, together with the springs 17, 18 thereby swing about the pivots 13 and 14 so that the horizontal position of the carrier and the parts associated with it is maintained.

The machine may run without rails or may be constructed as a rail vehicle.

We claim:

1. A self-propelled machine for holding and moving heavy work to be forged, comprising a wheeled frame, means for propelling the frame, a tongs for holding the work, a pair of bell-crank levers pivotally mounted at either side of said frame, a bar pivoted to one arm of each lever of each pair of said levers, upright rods pivoted to the other arms of said levers, helical springs disposed around said rods, a tongs-carrying member supported by said helical springs, and a single lifting cylinder by which said bell-crank levers can be turned about their pivots.

2. A self-propelled machine for holding and moving heavy work to be forged, comprising a wheeled frame, means for propelling the frame, a tongs for holding the work, a pair of bell-crank levers pivotally mounted at either side of said frame, a bar pivoted to one arm of each lever of each pair of said levers, upright rods pivoted to the other arms of said levers, helical springs disposed around said rods, members supported on said springs and slideable on said rods, pivots on said members, a tongs-carrying member, arms on said tongs-carrying member mounted on said pivots, and a single lifting cylinder by which said bell-crank levers can be turned about their pivots.

3. A self-propelled machine for holding and

moving heavy work to be forged, comprising a wheeled frame, means for propelling the frame, a tongs for holding the work, a pair of bell-crank levers pivotally mounted at either side of said frame, a bar pivoted to one arm of each lever of each pair of said levers, upright rods pivoted to the other arms of said levers, helical springs disposed around said rods, members supported on and partly enclosing said springs and slideable on said rods, pivots on said members, a tongs-carrying member, arms on said tongs-carrying member mounted on said pivots and a single lifting cylinder by which said bell-crank levers can be turned about their pivots.

4. A self-propelled machine for holding and moving heavy work to be forged, comprising a wheeled frame, means for propelling the frame, a tongs for holding the work, a pair of bell-crank levers pivotally mounted at either side of said frame, a bar pivoted to one arm of each lever of each pair of said levers, upright rods pivoted to the other arms of said levers, helical springs disposed around said rods, a tongs-carrying member supported by said helical springs, a buffer frame connected to one arm of each lever of each pair of said levers, resilient means whereby said buffer frame is normally held in a central position and a single lifting cylinder by which said bell-crank levers can be turned about their pivots.

5. A self-propelled machine for holding and moving heavy work to be forged, comprising a wheeled frame, means for propelling the frame, a tongs for holding the work, a pair of bell-crank levers pivotally mounted at either side of said frame, a bar pivoted to one arm of each lever of each pair of levers, upright rods pivoted to the other arms of said levers, helical springs disposed around said rods, a tongs-carrying member supported by said helical springs, a buffer frame connected to one arm of each lever of each pair of said levers, helical springs parallel to the axis of the tongs-carrying member whereby said buffer frame is held in a central position and a single lifting cylinder by which said bell-crank levers can be turned about their pivots.

6. A self-propelled machine for holding and moving heavy work to be forged, comprising a wheeled frame, means for propelling the frame, a tongs for holding the work, a pair of bell-crank levers pivotally mounted at either side of said frame, a bar pivoted to one arm of each lever of each pair of said levers, upright rods pivoted to the other arms of said levers, helical springs disposed around said rods, a tongs-carrying member supported by said helical springs, a buffer frame connected to one arm of each lever of each pair of said levers, apertured lugs on said buffer frame, apertured lugs on said tongs-carrying member, a rod fixed in the apertures in said last-mentioned lugs and slideable in the apertures in the first-mentioned lugs, sleeves on said rod slideable in said first-mentioned apertures, collars on said sleeves, a spring bearing against said collars and a single lifting cylinder by which said bell-crank levers can be turned about their pivots.

HERBERT DIENENTHAL
THEO ZIMMERMANN.
